United States Patent Office

Des. 226,532
Patented Mar. 20, 1973

226,532

CHANDELIER

Motoko Ishii, Tokyo, Japan, assignor to Yamagiwa
Electric Company, Ltd., Tokyo, Japan

Filed Apr. 13, 1971, Ser. No. 133,770

Term of patent 14 years

Int. Cl. D26—05

U.S. Cl. D48—3

Fig. 1.

Fig. 3.

Fig. 2.

FIG. 1 is a front view of a lighting fixture showing my new design;

FIG. 2 is a bottom plan view thereof; and

FIG. 3 is an enlarged fragmentary cross-sectional view taken on the plane indicated by lines 3—3 in FIG. 1.

I claim:

The ornamental design for a chandelier, as shown.
